UNITED STATES PATENT OFFICE.

LESHER W. VAN BUSKIRK, OF HIGH BRIDGE, NEW JERSEY, ASSIGNOR TO TAYLOR-WHARTON IRON AND STEEL COMPANY, OF HIGH BRIDGE, NEW JERSEY, A CORPORATION OF NEW JERSEY.

MEANS FOR REFINING PAPER STOCK.

Application filed October 1, 1923. Serial No. 665,982.

To all whom it may concern:

Be it known that I, LESHER W. VAN BUSKIRK, a citizen of the United States, residing at High Bridge, in the county of 5 Hunterdon and State of New Jersey, have invented certain new and useful Improvements in Means for Refining Paper Stock, of which the following is a specification.

In pulp refining engines of the Jordan 10 type, a rotatable cone, commonly called a plug, with straight blades or knives, cooperates with a fixed shell, commonly called a liner, with more or less angularly disposed blades. The motive of the latter arrangement is to retard the progress of the 15 pulp material. Pulp materials vary, however, and while some materials are retarded even to the extent of being burned under the frictional heat developed, other materials are afforded an uninterrupted passage through 20 the engine without having been acted upon by the blades. In any event, the results are indifferent and the action of the plug and liner is unmistakably a hit or miss grinding 25 action.

I have discovered, that, by causing the stock or pulp material to dwell with more or less frequent periodicity with respect to its passage through the engine and by causing 30 it to be coincidently shunted to and fro with respect to the plug and liner, I obtain a drawing action instead of the usual grinding action with the result that the yield is characterized by an abundance of long 35 fibers.

My invention consists in certain details of construction of the plug and liner and in the assemblage of said elements to secure the results stated, all as hereinafter more 40 particularly described and finally claimed.

In the accompanying drawings, forming a part hereof,

Figure 1 is a longitudinal sectional view of 45 mated plug and liner elements embodying my improvements.

Fig. 2 is a fragmentary plan view showing a development of the plug blades.

Fig. 3 is a similar view showing a development of the liner blades; and 50 Fig. 4 is a sectional detail of the dam or diverter construction.

In practicing the invention, I so construct and arrange the plug and liner that the stock or pulp material being acted upon is caused

to dwell at frequent intervals and to be 55 shunted repeatedly back and forth with relation to the plug and liner. The dwells are established by bridging alternate blades of the plug at points opposite one another and in proximity with and preferably slightly 60 in advance of right angle extensions of the liner blades.

The plug is represented generally by the numeral 5, and the liner by the numeral 6. Each of said elements, inclusive of the knives or blades, is preferably an integral construction of manganese steel toughened by appropriate heat treatment and quenching. They might, however, be constructed of other steel, or even of cast iron, or one of 70 said elements may be constructed of manganese steel and the other element of ordinary steel or cast iron; but the best results obtain under the preference indicated. At intervals dwells are established along the 75 surface of the plug by bridging alternate sets of blades 7, as indicated at 8 and 9 which represent web formations of the height of the blades. As illustrated in Fig. 4 one of the end walls is almost perpendicular and 80 the other is of sloping contour.

The blades 10 of the liner may have the usual step zigzag or obtuse angle formation, as indicated at 11, and may otherwise be as usual except that the steps are joined by 85 right angle extensions 12. The latter are disposed opposite the dwells or deflecting elements of the plug. The purpose and effect of this construction and arrangement is to cause the stock or pulp material to repeatedly change its course by alternately shunting it back and forth with relation to the plug and liner. It follows that the action of the blades on the stock is a drawing action rather than a grinding action 90 with the result that there is a remarkable 95 yield of long fibers and the product is uniformly superior to products of the conventional practice regardless of the nature of the stock.

The plug has openings 13 and 14 for the usual shaft (not shown) the openings 13 being established by an integral hub 15 which together with its spokes 16 is reinforced by endwise ranging webs 17. Since 100 the plug is preferably a casting of manganese steel and unmachineable the spokes 16 have inserted fillings 18 of machineable

metal to receive the fastenings of the usual wood end closure 19.

Having described my invention, I claim:—

- 5 1. Means for refining pulp material, comprising the combination with mated alloy steel plug and liner elements of the integral construction type, of provisions for establishing high frequency dwells in the passage of the stock and including bridging members between alternate blades of the plug, and means on the liner and co-operating with said bridging members for diverting the stock from one element to the other.
- 10 10. In a Jordan engine, the combination of bladed plug and liner elements, the blades
- 15 15. 2. In a Jordan engine, the combination of bladed plug and liner elements, the blades

of one of said elements having offset or angle formations, and adjacent blades of the other element having connecting webs or bridges which co-operate with the angle formations to divert the stock from one element to the other.

3. A plug for a Jordan engine having alternate sets of blades bridged by transverse webs substantially the height of the blades.

4. A plug for a Jordan engine having dams or bridging elements in staggered relation and whereof one end wall is substantially perpendicular and whereof the other end wall is of sloping contour.

In testimony whereof I affix my signature.

LESHER W. VAN BUSKIRK.
